Primary Examiner — Darcey E Gottschalk*Assistant Examiner* — Bailey M Knotts(74) *Attorney, Agent, or Firm* — Jeenam Park(57) **CLAIM**

The ornamental design for a LED light, as shown and described.

DESCRIPTION

FIG. 1 is a front, left and top perspective view of a LED light, showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an exploded view thereof; and,

FIG. 10 is an exploded view thereof.

The broken lines shown in the drawings illustrate portions of the LED light that form no part of the claimed design.

1 Claim, 10 Drawing Sheets(56)
